VULCANIZER

Filed Jan. 10, 1930

Inventor

Harry Erikson
By Joseph A. Miller

Attorney

UNITED STATES PATENT OFFICE

HARRY ERIKSON, OF LOWELL, MASSACHUSETTS, ASSIGNOR TO NORKO MFG. CO., OF PAWTUCKET, RHODE ISLAND

VULCANIZER

Application filed January 10, 1930. Serial No. 419,846.

This invention relates to vulcanizers and the primary object thereof is to provide improved means for maintaining uniform and constant pressure on the parts to be vulcanized and to effect gradual curing of the rubber to a firm and uniform consistency.

A further object of the invention is to provide pressure means which is automatically raised up from the work and maintained in a raised position upon manual release.

The invention further aims to provide simplified and economical means which occupies a minimum of space and which can be easily and quickly operated.

In the drawings:—

Figure 1 is a front elevation of the invention.

Figure 2 is a detail enlarged side elevation of one of the pressure devices; and,

Figure 3 is a top plan view of Figure 2.

In proceeding in accordance with the present invention a bed or table 1 is provided and on and against which the work, here shown as an inner-tube T is held and pressed. An inverted substantially U-shaped member 2 is carried by the bed 1 and over which the tube T is draped or supported. As shown in the drawings, a series of pressure devices are employed so as to enable a corresponding number of pieces of work to be vulcanized at the same time. The bed 1 may be either electrically or steam heated as may be preferred. Each

pressure device embodies a vertical post or standard 3 secured in any suitable way at its lower portion to the bed 1. A horizontal arm 4 has one end perforated to slidably and rotatably receive the post 3 therein and has its opposite end perforated to slidably receive the stem 5 of the pressure head 6. The head 6 is rigidly attached to the lower end of the stem 5 and has a stop washer 7 rigidly secured to its upper end so as to limit downward movement of the pressure head 6 under influence of a coil spring 8, which latter encircles the stem 5 and at one end engages the head 6 and at its opposite end engages the under face of the arm 4. The upper end of the post 3 is

formed with an integral and attenuated ear 9, which latter is received in the bifurcation 10 of a cam head 11, and is pivoted thereto by means of a pin 12. The cam head 11 engages with the upper face 13 at 55 one end of the arm 4 and is provided with a handle 14 to enable ready operation of the head. A coil spring 15 encircles the post 3 and at its upper end engages the underside of arm 4 and at its lower end engages a 60 washer 16 which is slidable on the post 3. A perforated member 17 receives the lower end of the post 3 therein and is provided with a set screw 18, which latter holds the member 17 in an adjusted position along the 65 length of the post 3. As shown in Figure 2 of the drawings the washer 16 is supported on the member 17, and by adjustment of the member 17 to various positions along the post 3, the pressure head 6 can be set in 70 varying relation to the bed 1, dependent upon the thickness of the work. As shown in Figure 1 of the drawings a plate or member 18 may be employed in instances of where the part to be vulcanized is of greater 75 area than that of the head 6, and in such instances the pressure head 6 bears against the plate 18.

In operation, the work is positioned on the bed 1 beneath the pressure head 6, the parts at this time occupying the position shown in Figure 2. The handle 14 is then thrown to the right of Figure 2 which causes the cam head 11 to act against the face 13, thereby depressing the arm 4 against the 80 action of the spring 15, and upon the head 6 engaging the work. It will be noted that the arm 4 continues its downward movement until the cam action ceases and compresses the spring 8 as shown at the center of Figure 1, whereby the spring 8 causes the head 6 to exert constant and uniform pressure 85 on the work.

Having thus described my invention what I claim as new and desire to secure 90 by Letters Patent is:

1. In a vulcanizer, a bed, a vertical post secured to the bed and extending upwardly therefrom, and having an ear on its upper end, a horizontal arm slidable on the post, 95

a cam member bifurcated to receive the ear and pivoted thereto and being engageable with the upper face of the arm, a pressure head having a stem slidably carried by the arm, a coil spring encircling the stem and engaged with the head and arm to tension the head, a member slidable on the post and having a screw to adjustably secure same to the post, and a coil spring encircling the post and engaged with the arm and with the said member to raise the arm upon release of the cam member.

2. In a vulcanizer, a bed, a vertical post secured to the bed and extending upwardly therefrom, a horizontal arm slidable on the post, a cam member pivoted to the post and engageable with the arm to depress the latter, a coil spring on the post engaged with and beneath the arm to urge the latter upwardly, a pressure head having a stem slidably carried by the arm, and a coil spring on the stem engaged with the arm and head to tension the latter.

3. In a vulcanizer, a bed, a post, a horizontal spring tensioned arm on the post, a cam member pivoted to the post and engaged with the arm to depress the latter against the action of the spring, and a spring tensioned work engaging pressure head carried by the arm.

4. In a vulcanizer, a bed, a vertically slidable upwardly spring tensioned member mounted on a post secured to the bed a spring tensioned work engaging pressure head carried by the member, and cam means for depressing the member against the action of its spring.

In testimony whereof I have signed my name to this specification.
